CLAIM

The ornamental design for an oven, microwave and/or warming drawer, as shown and described.

DESCRIPTION

FIG. 1 is a front view of an oven showing a first embodiment of our ornamental design;

FIG. 2 is a front view of an oven showing a second embodiment of our ornamental design;

FIG. 3 is a front view of an oven showing a third embodiment of our ornamental design; and,

FIG. 4 is a front view of an oven showing a fourth embodiment of our ornamental design.

Where included, broken lines showing environment or structure are for illustrative purposes only and form no part of the claimed design.
